United States Patent Office

Des. 186,837
Patented Dec. 8, 1959

186,837

AQUARIUM

Allan H. Willinger and Harding W. Willinger,
New Rochelle, N.Y.

Application November 10, 1958, Serial No. 53,325

Term of patent 14 years

(Cl. D91—2)

FIG.1

FIG.2

FIG.3

FIG.4

Figure 1 is a perspective view of an aquarium showing our new design;

Figure 2 is a rear elevational view thereof;

Figure 3 is an end elevational view taken from the left side of Figure 2; and

Figure 4 is a bottom view thereof.

The characteristic feature of our design resides in the cover member having the configuration shown.

We claim:

The ornamental design for an aquarium, substantially as shown and described.
